UNITED STATES PATENT OFFICE.

ONÉSIME LEMIEUX AND GEORGE LIBOIRON, OF MONTREAL, QUEBEC, CANADA.

DESIGN FOR A SIDE CAR FOR MOTORCYCLES.

58,037.

Specification for Design.

Patented May 31, 1921.

Application filed October 12, 1920. Serial No. 416,556. Term of patent 3½ years.

To all whom it may concern:

Be it known that we, ONÉSIME LEMIEUX and GEORGE LIBOIRON, both subjects of the King of Great Britain, residing at Montreal, in the Province of Quebec, Canada, have invented a new, original, and ornamental Design for Side Cars for Motorcycles, of which the following is a specification, reference being had to the accompanying drawing, forming part thereof.

The figure is a plan view of a side car showing our new design.

We claim:

The ornamental design for a side car for motorcycles as shown.

ONÉSIME LEMIEUX.
GEORGE LIBOIRON.
